UNITED STATES PATENT OFFICE.

GAYLE L. SQUIRE, OF HASTINGS, FLORIDA.

CHAIR.

1,350,041.

Specification of Letters Patent. Patented Aug. 17, 1920.

Application filed December 30, 1919. Serial No. 348,257.

To all whom it may concern:

Be it known that I, GAYLE L. SQUIRE, a citizen of the United States, residing at Hastings, in the county of St. John and 5 State of Florida, have invented a new and useful Chair, of which the following is a specification.

This invention relates to new and useful improvements in chairs and more particularly to chairs especially constructed for use in public halls, theaters or the like, wherein it is necessary to employ chairs wherein the seat portions thereof may be moved to a 10 position in substantially parallel relation 15 with the back thereof.

The primary object of the invention is to provide a chair of this character wherein the back will have pivotal connection with the seat portion thereof, whereby movement 20 of the back will produce a relative movement of the seat portion to move the seat portion out of the path of travel of persons entering between lines of chairs.

A further object of the invention is to 25 provide a means carried by the lower extremity of the back-rest of each of the chairs for contacting with the seat portion thereof for setting up a wedging action between the seat and back, when the seat is moved to 30 its open position, to cause a substantially rigid connection between the seat and back-rest to prevent movement of the seat portion with relation to the back-rest.

With the foregoing and other objects in 35 view which will appear as the description proceeds, the invention resides in the combination and arrangement of parts and in the details of construction hereinafter described and claimed, it being understood 40 that changes in the precise embodiment of the invention herein disclosed, may be made within the scope of what is claimed, without departing from the spirit of the invention.

45 Referring to the drawing:—

Figure 1 illustrates a side elevational view of a seat constructed in accordance with the present invention, one of the supporting legs thereof being removed,

50 Fig. 2 illustrates a rear elevational view of a portion of a seat.

Fig. 3 illustrates a fragmental detail view of a seat disclosing a connection between

the back-rest and the supporting legs thereof, and

Fig. 4 illustrates a fragmental sectional view in elevation, of this connection.

Referring to the drawing in detail, the reference character 5 designates the base or supporting legs of the seat which are provided with angularly disposed flanges 6, formed at the lower inner edges thereof, which flanges are apertured as at 7 to receive suitable securing means, not shown.

The supporting legs 5 are provided with 65 right angled supporting flanges 7' formed on the inner surfaces thereof, which provide stops or rests for the seat portion 8 of the chair, to support the seat portion in a horizontal position, when the same is in 70 use.

As shown, an upwardly extending arm 9 forms a part of each of the supporting legs 5, and provides a support for the pivot pin 10, which passes through a suitable opening 75 formed in the back-rest 11, the opening being disposed at a point in spaced relation with the lower end 12 of the back-rest, so that the upper portion of the back-rest acts as a lever to cause the operation of the seat 80 portion 8, in a manner to be hereinafter more fully described.

A segmental gear 13 is formed at the base of each of the side arms of the back-rest, the teeth thereof co-operating with the teeth 85 14 of the gear wheel 15 formed integral with each side member of the seat portion 8, which seat portion 8 is pivotally connected to the supporting legs 5 by means of the pins 16.

90 Disposed at the rear of the segmental gear 13, is a stop 17 formed integral with each of the side arms of the back-rest, the same being shown as having a forward curved portion contacting with a similar 95 curved portion of the gear wheel 15.

It will be seen that when the seat is in a position as indicated by Fig. 1 of the drawing, the stop 17 engages the gear 15 for restricting movement of the back with relation to the seat 8, and at the same time prevents movement of the seat portion 8 with relation to the back-rest.

100 In operation, the upper portion of the back-rest is grasped by the person to occupy 105 the seat, the back-rest is then moved to the

rear with the result that the teeth of the segmental gear revolve the gear wheel 15 forming a part of the seat portion 8 to cause the seat portion 8 to move to a position in 5 horizontal relation with the back-rest.

In order to move the seat to its inoperative position, it is necessary to move the back-rest in the opposite direction, which movement causes the seat portion to move 10 upwardly, to a position in parallel relation with the back-rest.

Having thus described the invention, what is claimed is:

In a chair, supporting legs, each of said 15 supporting legs having an upwardly extending arm, a back rest comprising spaced arms pivotally supported by the upwardly extending arm, each of said spaced arms having a segmental gear formed at the

lower end thereof, a pivoted seat portion positioned between the arms, segmental gears carried by the seat portion and coöperating with the first mentioned segmental gears, supporting flanges disposed under the seat and adapted to receive the seat portion when 25 the same is in a horizontal position, and a stop formed integral with each of the spaced arms, and adapted to engage a portion of the segmental gears of the seat portion for restricting movement of the back rest. 30

In testimony that I claim the foregoing as my own, I have hereto affixed my signature in the presence of two witnesses.

GAYLE L. SQUIRE.
